STEP CONSTRUCTION

Max Robert Georg Reichert, Berlin-Steglitz, Germany

Application August 15, 1955, Serial No. 528,254

11 Claims. (Cl. 72—96)

This invention relates to step construction and, more particularly, to a set of steps of the type consisting of a plurality of stringers which are stair-shaped at their top side and supported on stair heads or resting places constructed accordingly.

It is an object of the present invention to provide means for ensuring a reliable interconnection of the stringers forming the stairs.

With this and further objects in view, according to the present invention the stringers are provided, in at least one step of the set of steps, with dovetailed recesses which are open on top and extend transversely to the stringers, the recesses of adjacent stringers being aligned with each other and having a tapered cross section in at least two, but advantageously in three planes arranged at right angles to each other.

Other and further objects, features and advantages of the invention will be pointed out hereinafter and appear in the appended claims forming part of the application.

In the accompanying drawings several now preferred embodiments of the invention are shown by way of illustration and not by way of limitation.

Fig. 1 is a fragmentary perspective view of a part of a stringer having the invention applied thereto and being formed with a dovetailed recess in one step.

Fig. 2 is a plan view on a step formed of three stringers arranged side by side and having each a dovetailed recess.

Fig. 3 is a vertical section transversely through a step formed of three stringers arranged side by side and having each a dovetailed recess, the right-hand stringer engaging the wall of a building.

Fig. 4 is a vertical section through a stringer as per Fig. 1.

Fig. 5 is a fragmentary plan view of a set of steps laterally connected to the wall of a building.

Fig. 6 is a similar view showing a different direction of the taper of the dovetailed recesses in the upper and lower recessed steps.

Fig. 7 is a fragmentary plan view showing the attachment of a post for a railing, and

Fig. 8 is a section on line VIII-VIII of Fig. 7.

Similar reference numerals denote similar parts in the different views.

Referring now to the drawings in greater detail, and first to Fig. 1, it will be seen that the stringer 1 in this case in order to reduce its weight is constructed as a beam, preferably a pre-fabricated concrete beam, having a vertical web 1a in which a main reinforcing rod 1b is embedded, while the pressure plate 1c is folded at right angles in accordance with the shape of the steps. Provided in the portions of the pressure plate 1c forming the medium step of the illustrated fragmentary part of the stringer 1 is a dovetailed recess 2 which is tapered in three planes disposed at right angles at each other.

A number of stringers 1 arranged closely adjacent to each other and resting with their upper and lower ends on a landing or stair-head beam result in a more or less

2

wide stair. As shown by way of example in Fig. 2, the dovetailed recesses 2 provided in the parts of the pressure plate 1c forming the middle step are aligned with each other in such a way that it is possible to insert therein, 5 embedded in concrete, a continuous steel rod 3, preferably provided with transverse ribs 3a. The dovetailed recesses permit to apply the steel rod 3 in such a manner that the same is completely embedded in the concrete. This is shown especially in Fig. 3 which also indicates 10 that the steel rod 3 which advantageously is provided with transverse ribs for increasing the adhesion can be concreted in the wall 4 of the staircase in a corresponding length. The stair is thereby laterally anchored in a simple manner, whereby its stiffness is increased.

According to the invention a stair is composed of the stringers provided with dovetailed recesses in such a way that the reduced or tapered end of the recesses 2 of all stringers 1 are arranged in the same direction, except for the outer stringers of a stair whose recesses are always 15 inwardly tapered even if the reduced ends of the recesses in the remaining stringers are outwardly directed, as shown in Fig. 5, in order to receive the tension forces exerted upon the concrete plugs disposed in the recesses of the stringers.

20 The dovetailed formation of the recesses 2 on the one hand ensures that the concrete introduced therein from the top after the setting cannot evade in an upward direction. Furthermore, the special shape of the recesses ensures that the composite stringers participate uniformly 25 in the load or bearing pressure and behave similar to a uniform complete flight of stairs, without requiring a special internal transverse anchoring system which would be difficultly accessible from the top.

Stringers according to the invention, if they are of a 30 shorter length, are provided with recesses 2 at least in one step, while in case of a larger length such recesses 2 are provided at least in two steps of each stringer, as indicated in Fig. 6, in which the recesses 2 at the upper end are outwardly tapered except for the outer one, while the 35 recesses 2 at the lower end are all inwardly tapered. In this way, a particularly high strength and "plate effect" is achieved.

According to a further feature of the invention, and as 40 illustrated in Figs. 7 and 8, the outer stringers may be provided with additional outwardly tapered dovetailed recesses 5 for anchoring the railing posts 6. Said recesses 5 preferably are arranged in steps in which no recesses 2 for the transverse armouring are provided.

45 It is not a feature of the present invention to provide plate beams having one unilateral web as shown in Fig. 1, but solid stringers or stringers with T-shaped or U-shaped cross section may be used as well. However, where plate beams are used, it may be necessary to reinforce the pressure plate in the region of the dovetailed recesses.

50 While the invention has been described in detail with respect to certain now preferred examples and embodiments of the invention it will be understood by those skilled in the art after understanding the invention that various changes and modifications may be made without departing from the spirit and scope of the invention and it is intended, therefore, to cover all such changes and modifications in the appended claims.

I claim:

55 1. A stair comprising, in combination, a plurality of adjacent stepped stair segments, each stair segment having a plurality of stepped top faces respectively arranged at the same level and flush with the corresponding top faces of the other stair segments, the top faces of at least one horizontal set of top faces arranged on the same level being respectively each formed with a recess, said recesses being transversely aligned to form together a transversely extending channel in said one set

of top faces, each of said recesses tapering in said transverse direction toward one adjacent stair segment, and widening in downward direction away from the respective top face, each of said recesses having a bottom face downwardly inclined toward the adjacent stair segment; a transverse rod located in said transversely extending channel and supported on the uppermost points of said bottom faces of said recesses; and a concrete filler member completely filling said transverse channel and having a plurality of connected transverse sections respectively located in said recesses of said stair segments, each of said sections tapering in said transverse direction toward the adjacent section for holding said stair segments against movement in said transverse direction and widening in downward direction for holding said stair segments against relative displacement in vertical direction, each of said sections flaring in downward direction toward the adjacent stair segment so that said rod is embedded in said concrete filler member.

2. A stair comprising, in combination, a plurality of adjacent stepped stair segments, each stair segment having a plurality of stepped top faces respectively arranged at the same level and flush with the corresponding top faces of the other stair segments, the top faces of at least one horizontal set of top faces arranged on the same level being respectively each formed with a recess, said recesses being transversely aligned to form together a transversely extending channel in said one set of top faces, each of said recesses tapering in said transverse direction toward one adjacent stair segment, and widening in downward direction away from the respective top face, all said recesses tapering in one direction transversely and widening downwardly in a transverse direction opposite said one direction; and a concrete filler member completely filling said transverse channel and having a plurality of connected transverse sections respectively located in said recesses of said stair segments, each of said sections tapering in said transverse direction toward the adjacent section for holding said stair segments against movement in said transverse direction and widening in downward direction for holding said stair segments against relative displacement in vertical direction.

3. A stair comprising, in combination, a plurality of adjacent stepped stair segments, each stair segment having a plurality of stepped top faces respectively arranged at the same level and flush with the corresponding top faces of the other stair segments, the top faces of at least one horizontal set of top faces arranged on the same level being respectively each formed with a recess, said recesses being transversely aligned to form together a transversely extending channel in said one set of top faces, each of said recesses tapering in said transverse direction toward one adjacent stair segment, and widening in downward direction away from the respective top face, each of said recesses having a bottom face downwardly inclined toward the adjacent stair segment, all said recesses tapering in one direction transversely and widening downwardly in a transverse direction opposite said one direction, the bottom faces of all said recesses being downwardly inclined in said opposite transverse direction; a transverse rod located in said transversely extending channel and supported on the uppermost points of said bottom faces of said recesses; and a concrete filler member completely filling said transverse channel and having a plurality of connected transverse sections respectively located in said recesses of said stair segments, each of said sections tapering in said transverse direction toward the adjacent section for holding said stair segments against movement in said transverse direction and widening in downward direction for holding said stair segments against relative displacement in vertical direction, each of said sections flaring in downward direction toward the adjacent stair segment so that said rod is embedded in said concrete filler member.

4. A stair comprising, in combination, a plurality of adjacent stepped stair segments, each stair segment having a plurality of stepped top faces respectively arranged at the same level and flush with the corresponding top faces of the other stair segments, the top faces of at least one horizontal set of top faces arranged on the same level being respectively each formed with a recess, said recesses being transversely aligned to form together a transversely extending channel in said one set of top faces, each of said recesses tapering in said transverse direction toward one adjacent stair segment, and widening in downward direction away from the respective top face, each of said recesses having a bottom face downwardly inclined toward the adjacent stair segment; a transverse rod located in said transversely extending channel and supported on the uppermost points of said bottom faces of said recesses, said rod having a plurality of spaced ribs extending peripherally therefrom; and a concrete filler member completely filling said transverse channel and having a plurality of connected transverse sections respectively located in said recesses of said stair segments, each of said sections tapering in said transverse direction toward the adjacent section for holding said stair segments against movement in said transverse direction and widening in downward direction for holding said stair segments against relative displacement in vertical direction, each of said sections flaring in downward direction toward the adjacent stair segment so that said rod is embedded in said concrete filler member.

5. A stair comprising, in combination, a plurality of adjacent stepped stair segments, each stair segment including a base portion and a stepped portion located at least partly on said base portion and having a plurality of stepped top faces respectively arranged at the same level and flush with the corresponding top faces of the other stair segments, the top faces of at least one horizontal set of top faces arranged on the same level being respectively each formed with a recess, said recesses being transversely aligned to form together a transversely extending channel in said one set of top faces, each of said recesses tapering in a transverse direction toward one adjacent stair segment and away from the respective base portion, each of said recesses widening in downward direction away from the respective top face and deepening toward the respective base portion; a transverse reinforcing member located in said channel; and filler means completely filling said transverse channel and securing said member therein, said means having a plurality of connected transverse sections respectively located in said recesses of said stair segments, each of said sections tapering in said transverse direction toward the adjacent section for holding said stair segments against movement in said transverse direction and widening in downward direction for holding said stair segments against relative displacement in vertical direction.

6. A stair comprising, in combination, a support having a vertical face, a plurality of adjacent stepped stair segments including one outermost stair segment adjacent said vertical face of said support and an opposite outermost freely projecting stair segment, each stair segment having at least one face arranged in the same plane and flush with the corresponding faces of the other stair segments forming with the same a set of corresponding faces, the faces of at least one set of corresponding faces being respectively each formed with a recess, said recesses being transversely aligned to form together a transversely extending channel in said one set of corresponding faces, the recess in at least said freely projecting outermost stair segment narrowing in transverse direction toward the adjacent segment, a reinforcing member passing through said transverse channel extending at least from a point within said recess in said outermost freely projecting stair segment to a point within said support and firmly anchored to the latter; and a hard filler member completely filling said transverse channel embedding

said reinforcing member, said hard filler member having a plurality of connected transverse sections respectively located in said recesses of said stair segments, at least the section in said recess in said outermost freely projecting stair segment narrowing in said transverse direction toward the adjacent section for holding, in combination with said reinforcing member anchored in said support, all of said stair segments firmly secured to said support.

7. A stair comprising, in combination, a support having a vertical face, a plurality of adjacent stepped stair segments including one outermost stair segment adjacent said vertical face of said support and an opposite outermost freely projecting stair segment, each stair segment having a plurality of stepped top faces respectively arranged in the same plane and flush with the corresponding faces of the other stair segments forming with the same a set of corresponding faces, the faces of at least one set of corresponding faces being respectively each formed with a recess, said recesses being transversely aligned to form together a transversely extending channel in said one set of corresponding faces, each of said recesses narrowing in transverse direction toward one adjacent segment, and widening in downward direction away from the respective top face, a reinforcing member passing through said transverse channel extending at least from a point within said recess in said outermost freely projecting stair segment to a point within said support and firmly anchored to the latter; and a concrete filler member completely filling said transverse channel embedding said reinforcing member, said hard concrete member having a plurality of connected transverse sections respectively located in said recesses of said stair segments, at least the section in said recess in said outermost freely projecting stair segment narrowing in said transverse direction toward the adjacent section for holding, in combination with said reinforcing member anchored in said support, all of said stair segments firmly secured to said support and widening in downward direction for holding said stair segments against relative displacement in vertical direction.

8. A stair comprising, in combination, a support having a vertical face, a plurality of adjacent stepped stair segments including one outermost stair segment adjacent said vertical face of said support and an opposite outermost freely projecting stair segment, each stair segment having a plurality of stepped top faces respectively arranged in the same plane and flush with the corresponding faces of the other stair segments forming with the same a set of corresponding faces, the faces of at least one set of corresponding faces being respectively each formed with a recess, said recesses being transversely aligned to form together a transversely extending channel in said one set of corresponding faces, the recess in said freely projecting outermost stair segment narrowing in transverse direction toward said support, the recess in the remainder of said plurality of stair segments narrowing in transverse direction toward said freely projecting outermost stair segment, and each of said recesses widening in downward direction away from the respective top face a reinforcing member passing through said transverse channel extending at least from a point within said recess in said outermost freely projecting stair segment to a point within said support and firmly anchored to the latter; and a concrete filler member completely filling said transverse channel embedding said reinforcing member, said hard concrete member having a plurality of connected transverse sections respectively located in said recesses of said stair segments, at least the section in said recess in said outermost freely projecting stair segment narrowing in said transverse direction toward the adjacent section for holding, in combination with said reinforcing member anchored in said support, all of said stair segments firmly secured to said support and widening in downward direction for holding said

stair segments against relative displacement in vertical direction.

9. A stair comprising, in combination, a support having a vertical face, a plurality of adjacent stepped stair segments including one outermost stair segment adjacent said vertical face of said support and an opposite outermost freely projecting stair segment, each stair segment having at least one face arranged in the same plane and flush with the corresponding faces of the other stair segments forming with the same a set of corresponding faces, the faces of at least one set of corresponding faces being respectively each formed with a recess, said recesses being transversely aligned to form together a transversely extending channel in said one set of corresponding faces, the recess in at least said freely projecting outermost stair segment narrowing in transverse direction toward the adjacent segment, a reinforcing member passing through said transverse channel extending at least from a point within said recess in said outermost freely projecting stair segment to a point within said support and firmly anchored to the latter; a hard filler member completely filling said transverse channel embedding said reinforcing member, said hard filler member having a plurality of connected transverse sections respectively located in said recesses of said stair segments, at least the section in said recess in said outermost freely projecting stair segment narrowing in said transverse direction toward the adjacent section; and a concrete connecting member extending laterally from said outermost stair segment adjacent said vertical face of said support and fixedly connected to one outermost transverse section of said filler member, said support being formed with an opening, and said connecting member being adapted to fill said opening for connecting said outermost freely projecting stair segment to said support.

10. A stair as set forth in claim 9, wherein said outermost freely projecting stair segment has at least one additional top face thereof formed with a recess tapering from and downwardly inclined toward said one side of said stair, and including a railing post located partly in said recess and a filler member filling said recess and securing said post therein.

11. A stair comprising, in combination, a plurality of adjacent stepped stair segments, each stair segment having a plurality of stepped top faces respectively arranged at the same level and flush with the corresponding top faces of the other stair segments, the top faces of at least one horizontal set of top faces arranged on the same level being respectively each formed with a recess, said recesses being transversely aligned to form together a transversely extending channel in said one set of top faces, each of said recesses tapering in said transverse direction toward one adjacent stair segment, and widening in downward direction away from the respective top face, each of said recesses having a bottom face downwardly inclined toward the adjacent stair segment; a transverse rod located in said transversely extending channel and supported on the uppermost points of said bottom faces of said recesses, said rod extending laterally from one side of said stair; a concrete filler member completely filling said transverse channel and having a plurality of connected transverse sections respectively located in said recesses of said stair segments, each of said sections tapering in said transverse direction toward the adjacent section for holding said stair segments against movement in said transverse direction and widening in downward direction for holding said stair segments against relative displacement in vertical direction, each of said sections flaring in downward direction toward the adjacent stair segment so that said rod is embedded in said concrete filler member; and a concrete connecting member extending laterally from said one side of said stair and from one outermost stair segment and fixedly connected to one outermost transverse section of said filler member, said connecting member being adapted to

fill an opening in a wall adjacent said stair for holding the lateral extension of said rod in said opening and for connecting said stair and said rod to said wall, the other outermost stair segment having at least one additional top face thereof formed with a recess tapering from and downwardly inclined toward said one side of said stair, and including a railing post located partly in said recess, and a filler member filling said recess and securing said post therein.
